UNITED STATES PATENT OFFICE.

WALTER BIXBY, OF DORCHESTER, MASSACHUSETTS, ASSIGNOR TO SHAWMUT ENGINEERING COMPANY, OF DORCHESTER, MASSACHUSETTS, A CORPORATION OF MASSACHUSETTS.

MECHANISM FOR AND METHOD OF THREADING YARN CARRIERS.

Application filed June 13, 1925. Serial No. 36,982.

My invention relates to carpet manufacture and aims to provide improved mechanism for and methods of placing or laying the tufting yarns in yarn carriers or tube frames, particularly of the type equipped with wall- or slot-threading receivers or tubes, as contrasted with those through which the yarns must be inserted or drawn by passing their ends through the tube bores. Also included among the objects of my invention is the provision of an improved receiver or tube of said wall- or slot-threading type, claims for which are contained in my divisional application Serial No. 151,697, filed November 30, 1926.

In the drawings showing by way of illustration one form of mechanism embodying my invention and adapted for use in practicing the method thereof:

20 Fig. 1 is a plan view of the yarn placing mechanism with a yarn carrier in position thereon;

25 Fig. 2 is a vertical transverse section through the mechanism of Fig. 1, looking toward the left in said figure, the parts being in their starting position;

30 Fig. 3 is a view similar to Fig. 2 but with the parts in the position which they assume subsequent to the yarn laying and trimming operations, the yarn spool having been transferred to its position upon the carrier or tube frame;

35 Figs. 4, 5 and 6 are respectively a plan view and opposite side elevations, upon a larger scale, of the improved yarn receiver or tube, and

Fig. 7 is a detail view in end elevation showing the control mechanism.

Referring first to Figs. 4 to 6, the yarn receiver or tube there shown, and also seen upon a smaller scale in Figs. 1 to 3, is of the wall- or slot-threading or open-side type and constitutes an improvement upon the device of the patent to Perry No. 1,520,595, dated December 23, 1924. The tube, indicated as a whole at 1, is formed from a suitably shaped blank, preferably of sheet metal, which is folded into a generally tubular form. The side edges of the blank are so formed and spaced as to provide an undu-

latory slot 2 extending the length of the enclosed portion of the tube in a wall or walls thereof.

As best seen in Fig. 4 said slot leads from the trough or mouth 3 of the tube, extending first transversely and herein diagonally across the upper wall 4 from a point adjacent one side wall 5 and then down and along the opposite side wall 6. Said last mentioned side wall 6 desirably projects longitudinally somewhat beyond the other side wall 5, as indicated at 7, see particularly Fig. 6, and merges into a lip or guide 8 extending toward the opposite side of the tube and in substantially the same plane with the top wall 4 of the latter.

Said guide 8 will engage a yarn which is drawn lengthwise along and above the tube and, cooperating with the adjacent inclined edge 9 at the mouth of the slot, will positively compel the yarn to enter the slot instead of slipping off to either side of the tube, as may frequently happen with a tube such as that of the Perry patent wherein the slot mouth is in a side wall. The yarn may therefore be drawn directly in alignment with the tube, and no transverse movement of or pull upon the yarn is required to cause it to enter the slot, as would be necessary in the absence of some such guiding or retaining member as the lip 8 herein. Said lip, which preferably extends upwardly at least to the level of the top wall of the tube and is desirably inturned, also assists in retaining the yarn in the tube when threaded.

Referring now to Figs. 1, 2 and 3, a series of the tubes 1 is supported on a suitable carrier bar 10 provided with bearing supports 11 for one or more spools. Said tubes, carrier bar and spool supports constitute a so-called yarn carrier or tube frame, herein illustrated as holding but one spool 12, the threading mechanism being of a corresponding length. Obviously, however, the mechanism and method of my present invention are applicable equally well to "wide work" where a tube frame capable of holding two, three, or more spools is employed as, for example, in the patents to Hathaway and

Bixby #1,512,928 and #1,522,778, dated October 28, 1924 and January 13, 1925, respectively.

Said yarn placing or threading mechanism is mounted on suitable framing herein including the side frames or uprights 13, 14 between which extends the tube frame support 15 provided with suitable means such as the clips 16, Figs. 2 and 3, for holding the tube frame thereon during the yarn laying or threading operation.

The yarn spool 12 is positioned preparatory to and during the first stage of the yarn laying operation in suitable spool holders in brackets 17 projecting forwardly from the machine frame. Said holders include the opposed cups 18, 19 rotatable in said brackets and provided with circumferential teeth 20 meshing with pinions 21, Figs. 2 and 3, preferably one adjacent each of said cups 18, 19 and fixed on an adjusting shaft 22 also rotatably supported upon said brackets. Said shaft may be turned as by the hand wheel 23, Fig. 1, manually to take up the slack in or adjust the tension of the yarns, the spool being prevented from turning in said cups 18, 19 as by means of the spring-pressed pin 24 engageable with a corresponding recess in the adjacent spool head. Said adjusting shaft and connections for manual adjustment of the cups may be substantially as shown in the patent to Lea 1,191,109, dated July 11, 1916.

Preferably means is provided to turn the cups 18, 19 and the spool supported therein automatically at certain times. As herein illustrated, the cup 18 at the left, Fig. 1, has an axial stem or stub shaft 25 extending outwardly beyond the adjacent part of the bracket 17. Loosely surrounding said stub shaft is a gear 26 having a hub 27 rotatable in said bracket. Between the adjacent faces of the cup and of said gear is a friction member or disk 28 surrounding a hub portion 29 on the cup and seating within a recess in the gear.

The outer end of said stub shaft 25 is threaded to receive a nut 30 intermediate which and the outer face the gear hub 27 is a coil spring 31. By means of said nut the tension of said spring may be adjusted so as to hold the cup and friction disk against the gear under the desired pressure, preferably just sufficient to prevent undesired turning movement of the cups and spool, and to cause them to be rotated with the gear 26 when the latter is driven. Said spool and its cups may, however, be turned relatively to the gear 26 to take up any slack in the yarns through the medium of the hand wheel previously mentioned.

It will be understood that by means of said gear 26 the tension upon the yarn during laying thereof may be governed or controlled, herein automatically, said gear

being driven in any suitable manner, herein by the gear segment 32, more fully described later. Dependent upon the speed of turning thus imparted to the spool the yarn tension may be decreased to any desired extent or wholly neutralized.

The yarn ends 34 are held in the desired spaced relation by a suitable clamp or spacer 35, Figs. 2 and 3, the latter being supported for the threading operation in a clamp holder 36 extending longitudinally of the machine. The yarns then extend upwardly from the spool in the spool holders of the machine, substantially in the manner shown in Fig. 2, passing over the tube frame and directly above and across the inner ends of the respective tubes 1. If now the yarns and the tube frame be moved relatively to each other in a direction longitudinally of the tubes, the individual yarns will be engaged with the slots of the respective tubes and be laid or threaded into the latter through said slots.

In the present instance said clamp holder 36 is adapted to be moved while the tubes are held stationary and for this purpose it is mounted on arms 40 keyed upon a rock shaft 41 having suitable bearings in the side frame members. The clamp holder and clamp supported therein are thus movable to the desired extent relatively to the tube frame, preferably through a distance approximately equal to or somewhat exceeding the length of the tubes, so that the yarns are drawn entirely through the slots in the latter and thus passed into the tube bores.

Any suitable means may be employed for effecting said movement of the clamp holder, said means herein including, as best seen in Figs. 2 and 3, a floating link 42 pivoted at 43 to the arm 40 at the left of the machine as viewed in Fig. 1 and, at its opposite end pivotally connected at 44 to a lever 45 supported for rocking movement on a shaft 46 extending between the side frame members. Said lever 45 carries a cam roll 47 travelling in a cam path 48 formed in one side face of a cam 49. Said cam is fixed upon a drive or cam shaft 50 to which the power may be applied. Said cam path is formed to provide the desired movement of the clamp holder, the latter being preferably moved inwardly, toward the right in Figs. 2 and 3, during one half revolution of the cam and returned during the succeeding half revolution.

As previously stated, it is desirable positively to turn the spool during the yarn placing or threading operation to govern the yarn tension, and for this purpose the gear segment 32 above referred to and which meshes with the gear 26 is mounted on an arm 51 also rotatably supported by the shaft 46 and desirably formed integrally

with the lever 45 so as likewise to be controlled by the cam 49. It will thus be seen that during movement of the clamp holder to lay the yarns in the tubes the gear segment 32 will simultaneously be moved upwardly at a proportionate speed, rotating the spool in a counterclockwise direction as viewed in Figs. 2 and 3 and unwinding the yarn. The tension upon the yarn is thus controllable, the yarn being fed off from the spool at the desired rate to keep it slack or to prevent any such tension thereon as might withdraw the yarn ends from the clamp.

15 The series of threaded yarn ends are desirably trimmed by suitable mechanism. Prior to such trimming operation the machine is preferably stopped automatically and the spool 12 removed from its holders 20 on the machine, as shown in Figs. 1 and 2, and transferred into its bearing supports 11 upon the tube frame, as indicated in Fig. 3. The yarns may then be trimmed without danger of disarranging them by a subsequent 25 shifting of the spool.

The trimming mechanism herein includes a fixed blade 55 extending longitudinally along the tube frame support, and a co-operating movable blade 56. Said movable 30 blade is carried by a cross piece 57 secured at its opposite ends to the vertically movable bars 58 having suitable bearings and guides 59, 60 upon the side frame members. One or both of said bars, herein that at the 35 left of the machine as viewed in Fig. 1, is formed as a rack, see Figs. 2 and 3, having teeth 61 with which meshes a gear segment 62 on a lever arm 63 formed as one arm of a bell crank mounted for rocking movement 40 on a shaft 64, also supported in the frame. The other arm 65 of said bell crank carries at its outer end a cam roll 66 movable in a cam path 67 formed in a suitable cam upon the cam shaft 50. As herein illustrated said cam path 67 and the cam path 48 previously 45 mentioned are formed upon the opposite side faces of the same cam 49, although obviously separate cams may be employed if desired.

50 The parts last described are constructed and arranged properly to time the movements of the blade 56, desirably so that the shearing takes place shortly after the completion of the yarn laying operation and with the parts substantially in the position 55 illustrated in Fig. 3, the machine being momentarily stopped between the yarn laying and the shearing operations to permit the spool to be shifted onto the tube frame. 60 With the parts positioned as shown in Fig. 3 continued operation of the machine will again lift the movable knife and return the clamp holder to the starting position, shown in Fig. 2, where it is ready to receive the 65 clamp of the next spool. The spool turning

mechanism is also restored to its original position, as in said Fig. 2.

While power may be applied to the shaft 50 by any suitable means I have herein shown, see particularly Figs 1 and 7, an improved driving and control mechanism which is adapted for general use but which cooperates particularly with the yarn laying mechanism herein disclosed. Said mechanism includes a power receiving element 70 illustrated as a loose pulley 70 mounted upon the outer end of said shaft 50 and driven in any suitable manner at the desired speed. Upon its inner face it is formed with a circumferential series of laterally projecting 75 lugs 72 adapted to take against a finger 73 carried by a pivoted yoke 74 straddling a sleeve 75 secured to the shaft 50. Said yoke is pressed toward the loose pulley as by means of a spring 76 intermediate the sleeve 80 and an ear 77 on the yoke.

When the finger 73 is permitted to move, under influence of its spring, to the right in Fig. 1 and into the path of the lugs 72, it will be engaged by one of the latter and carried around with it, thereby imparting rotation to the cam shaft 50 to which the finger is secured through the yoke 74 and sleeve 75. If, however, the finger is held out of the path of the lugs 72, as shown in Fig. 1, no movement will be imparted to the shaft 50 and the machine will remain stationary.

To control said finger there is provided a hand lever 78 pivotally supported at 79 upon a boss 80 on the adjacent side frame. Secured to said lever are a pair of yoke-like arms 81, 82, see Fig. 7, provided at their outer ends with cams 83, 84 respectively movable radially of the shaft into and out of the path of the finger 73 by movement of the lever 78 in one or the opposite directions.

As illustrated in Figs. 1 and 7 the control lever 78 is down, and the cam 84 is moved in toward the shaft, holding the finger 73 out of engagement. To start the machine the lever is moved by the operator to its other position, that is, up. The cam 84 is thereby withdrawn, while the other cam 83 is moved into the path of the finger. The latter, thrown toward the pulley by its spring, will be engaged and carried around by the next approaching lug 72, in a counterclockwise direction, Fig. 7, turning the shaft 50. At the end of approximately a half revolution of the shaft, the finger 73 will come into engagement with the cam 83 and thereby be withdrawn from engagement with the lug 72. The machine accordingly is stopped automatically.

The arrangement of the cams 83, 84 is desirably such that said automatic stopping of the machine occurs just after the yarns have been laid in the tubes but before they have been trimmed, that is, just

prior to the position of the parts illustrated in Fig. 3. The operative may then remove the spool from its holders on the machine and install it on the tube frame, as shown in said Fig. 3. To complete the operation, the operative moves the control lever 78 in the opposite direction, that is, down, withdrawing the cam 83 and again moving the cam 84 in. The finger will then be engaged by the next lug 72 and carried round a further half revolution until again moved out by the cam 84, again stopping the machine. During said last half revolution the yarns are trimmed and the various parts are returned to the position of Figs. 1, 2 and 7, ready for placing and trimming the yarns of the next spool. The control lever 78 is releasably held in either of its positions as by the spring 85 upon the machine frame having seats respectively receiving the stop 86 on the lever in one or the other of its positions.

It will thus be seen that by the simple driving connections and control means described the machine may be started by the operative under his manual control and that it will automatically be stopped at the desired time, herein just prior to trimming of the yarns. Opposite movement of the same control lever will again start the machine, which completes its cycle of operations, the parts returning to their original position ready for the next cycle, and again automatically stopping. Obviously the movements above described may be otherwise arranged and timed or the complete cycle performed without stopping the machine, if desired. It will be understood that while I have illustrated an improved form of so-called "self-threading" or wall threading yarn or thread receiver the threading mechanism and method are equally applicable for use with any receiver adapted to have the yarn or thread passed through a wall thereof, such for example as in said patent to Perry, or in the patent to Johnson 1,561,433, dated November 10, 1925, whether such receiver has an open slot as in the Perry patent or a closed or partly closed slot or slit the walls of which are to be sprung apart in threading, as in the Johnson patent. The improved receiver or tube, and tube frame, herein illustrated are claimed in my divisional application, Serial No. 151,697.

My invention is not limited to the particular embodiment shown and described herein, its scope being set forth in the following claims.

60. Claims.

1. Mechanism for use in carpet manufacture for placing yarns in a tube frame having tubes of the slotted type, comprising in combination with a series of slotted tubes and their frame, a support for said frame,

spool holding means, a clamp for holding the yarn ends in spaced relation, a movable holder for said clamp, and means for moving said holder relatively to the tube frame to engage the yarns with the slots of the respective tubes and to draw them into the tube bores.

2. Mechanism for use in carpet manufacture for placing the tufting yarns in the slotted tubes of a tube frame, comprising a support for the tube frame, spool holding means, a yarn spacing clamp and a holder therefor, means supporting said holder for movement lengthwise the tubes, cam means, and link connections therewith for operating said holder supporting means.

3. Mechanism for use in carpet manufacture for placing the tufting yarns in the slotted tubes of a tube frame, comprising a support for the tube frame, spool holding means, a yarn spacing clamp and a holder therefor, means supporting said holder for movement lengthwise the tubes, cam means, and link connections therewith for operating said holder supporting means and for turning said spool holding means during movement of said holder.

4. Mechanism for use in carpet manufacture for placing the tufting yarns in the slotted tubes of a tube frame, comprising a support for the tube frame, spool holding means, a yarn spacing clamp and a holder therefor, means supporting said holder for movement lengthwise the tubes, and means for moving said holder.

5. Mechanism for use in carpet manufacture for placing the tufting yarns in the slotted tubes of a tube frame, comprising a support for the tube frame, spool holding means, a yarn spacing clamp and a holder therefor, means supporting said holder for movement lengthwise the tubes, means for moving said holder, and means for trimming the yarn ends.

6. Mechanism for use in carpet manufacture for placing the tufting yarns in the slotted tubes of a tube frame, comprising a support for the tube frame, spool holding means, a yarn spacing clamp and a holder therefor, means supporting said holder for movement lengthwise the tubes, means for moving said holder and mechanism for turning said spool holding means during movement of said holder.

7. Mechanism for use in carpet manufacture for placing the tufting yarns in the slotted tubes of a tube frame, comprising a support for the tube frame, spool holding means, a yarn spacing clamp and a holder therefor, means supporting said holder for movement lengthwise the tubes, means for moving said holder, mechanism for turning said spool holding means during movement of said holder, and means for trimming the yarn ends.

8. Mechanism for laying yarns in a yarn carrier having receivers of the slotted type, comprising a support for the yarn carrier, a yarn-end spacer and a holder therefor, and means for moving said holder so as to draw the yarns along the respective receivers and lay them therein.

9. Mechanism for laying yarns in a yarn carrier having receivers of the slotted type, comprising a support for the yarn carrier, spool holding means, a yarn-end spacing clamp, a clamp holder, and means for producing relative movement of said carrier and clamp holder thereby to lay the yarns in the respective receivers.

10. Mechanism for laying yarns in a tube frame having tubes of the slotted type, comprising a support for the tube frame, a yarn clamp, and means to produce relative movement of the tube frame and clamp thereby to lay the yarns in the respective tubes through the slots thereof.

11. Mechanism for laying yarns in the slotted receivers of a yarn carrier, comprising a carrier support, a yarn spacer and a holder therefor, and means relatively to move said carrier support and holder thereby to engage and lay the yarns in the respective receivers.

12. Mechanism for laying yarns in the slotted receivers of a yarn carrier, comprising spool holding means, a carrier support, a yarn end clamp and a holder therefor, and means relatively to move said carrier support and holder thereby to engage and lay the yarns in the respective receivers.

13. Mechanism for laying yarns in the receivers of a yarn carrier of the slot-threading type, comprising spool holding means, a carrier support, means to hold the yarn ends in spaced relation, and means relatively to move said carrier support and the yarns thereby to engage and lay the latter in the respective receivers.

14. Mechanism for laying yarns in the receivers of a yarn carrier of the slot-threading type, comprising spool holding means, a carrier support, means to hold the yarn ends in spaced relation, means relatively to move said carrier support and the yarns thereby to engage and lay the latter in the respective receivers, yarn-end trimming means, means to stop the mechanism subsequent to the laying of the yarns and prior to the operation of said trimming means to permit transfer of the spool from said spool holding means to the yarn carrier, and means for operating said trimming means upon subsequent starting of the mechanism.

15. Mechanism for laying yarns in the receivers of a yarn carrier of the slot-threading type, comprising spool holding means, a carrier support, means to hold the yarn ends in spaced relation, means relatively to move said carrier support and the yarns thereby

to engage and lay the latter in the respective receivers, yarn-end trimming means, means to stop the mechanism subsequent to the laying of the yarns and prior to operation of said trimming means to permit transfer of the spool from said spool holding means to the yarn carrier and means for operating said trimming means upon subsequent starting of the mechanism and for returning the parts to their original or starting position.

16. Mechanism for laying yarns in the slotted receivers of a yarn carrier, comprising a carrier support, a yarn end clamp and a holder therefor, spool holding means, means relatively to move said carrier support and holder thereby to engage and lay the yarns in the respective receivers, yarn-end trimming means, and means to stop the mechanism subsequent to the laying of the yarns and prior to operation of said trimming means to permit transfer of the spool from said spool holding means to the yarn carrier.

17. Mechanism for laying yarns in a yarn carrier having receivers of the slotted type, comprising a support for the yarn carrier, a yarn end spacing clamp, a clamp holder, means to produce relative movement of the carrier and clamp holder thereby to lay the yarns in the respective receivers through the slots thereof, and means to rotate the spool during the laying operation thereby to govern the yarn tension.

18. Mechanism for laying yarns in a yarn carrier having receivers of the slotted type, comprising a support for the yarn carrier, a yarn-end spacer, means to produce relative movement of said carrier and spacer thereby to lay the yarns in the respective receivers through the slots thereof, and means for governing the tension upon the yarn during the laying operation.

19. In mechanism for placing yarns in the receivers of a yarn carrier in carpet manufacture, the combination with means for placing the yarns, of means mechanically associated with said yarn placing means automatically to turn the spool in a direction to unwind the yarn thereby to reduce or wholly neutralize the tension thereon while being placed in the receivers of the carrier.

20. In mechanism for placing yarns in the receivers of a yarn carrier in carpet manufacture, the combination with means for placing the yarns, of automatic means operating during placing of the yarns for positively turning the spool on which the yarns are wound thereby to control the tension on the yarns at said time.

21. Mechanism for placing yarns in the receivers of a carrier in carpet manufacture comprising the combination with spool holding means, a carrier support and means to place the yarns in the receivers thereof, of

means automatically to govern the tension on the yarn during the placing operation by turning the spool at said time.

22. Mechanism for placing yarns in the receivers of a carrier in carpet manufacture comprising the combination with spool holding means, a carrier support and means to place the yarns in the receivers thereof, of automatic means positively to feed the yarns off the spool while they are being placed in said receivers.

23. In mechanism for placing yarns in the receivers of a yarn carrier in carpet manufacture the combination therewith of a support on the mechanism for a yarn spool, said support including opposed, rotatable cups adapted to receive the spool heads, manual means for turning said cups to adjust the yarn tension, automatic means for turning said cups, and connecting means intermediate said automatic means and cups affording driving connections between the same but permitting said manual adjustment.

24. In a machine for placing yarns in the tubes of a tube frame, a pair of opposed rotatable cup-like members for supporting a spool, means preventing relative movement between said members and spool, automatic means for turning said cup-like members and spool, and means whereby said members and spool may be manually turned independently of and without interference with said automatic means.

25. In a machine for placing yarns in the tubes of a tube frame, a rotatable support for a spool having means to prevent turning of the spool relatively thereto, automatic means at times to rotate said support and spool, and other means manually to rotate said support and spool for yarn tension adjusting purposes.

26. In a machine for placing yarns in the tubes of a tube frame, means on the machine for rotatably supporting a spool, manual means cooperating therewith to turn the spool for yarn tension adjusting purposes, and other means automatically to turn said spool at certain times.

27. In a machine for placing yarns in the tubes of a tube frame, a rotatable support for a yarn spool on the machine, manual means for turning said support to adjust the yarn tension, and automatic means also to turn said support at certain times.

28. In a machine for placing yarns in the tubes of a tube frame, a pair of opposed rotatable cups holding a spool, at least one of said cups having circumferential teeth, manually operable mechanism including a gear engaging said teeth, a member having frictional engagement with one of said cups, a gear frictionally engaging said member and adapted to rotate said cups through said member, and mechanism for driving said gear.

29. In a machine for placing yarns in the tubes of a tube frame, a rotatable support for a yarn spool, power operable means and also manual means for turning said support, and a friction clutch connection between said power-operable means and support permitting operation of said manual means independently of said power-operable means.

30. In a machine for placing yarns in the tubes of a tube frame, a rotatable support for a yarn spool on the machine, power operable means and also manual means for turning said support, and means operatively connecting said power-operable means and support but permitting turning thereof by said manual means.

31. That method of laying a series of spooled yarns in the respective slotted receivers of a yarn carrier which comprises rotatably supporting the yarn spool, holding the yarn ends in spaced relation and in approximate parallelism with the slotted receivers, moving the yarns lengthwise the receivers thereby to lay them therein, and rotating the yarn spool in a direction to feed off the yarns while so moving them.

32. That method of laying a series of yarns in the respective slotted tubes of a tube frame which comprises rotatably supporting a spool having the yarns wound on it, holding the yarn ends in spaced relation and in substantial parallelism with the respective tubes, engaging the yarns in the slots of the respective tubes and moving them therethrough to lay them into the tubes and simultaneously turning the spool thereby to control the yarn tension during laying of the yarns.

33. That method of laying a series of yarns in the respective slotted tubes of a tube frame which comprises supporting the yarns in spaced relation and in substantial parallelism with the respective tubes, moving the yarns lengthwise the tubes to lay them therein through the slots of the latter, and governing the tension of the yarns while so moved.

34. That method of laying a series of yarns in the respective slotted tubes of a tube frame which comprises supporting the tube frame in fixed position, holding the yarns in spaced relation, and drawing said spaced yarns over the receiving ends of the tubes and in a direction parallel to the axes of the latter while effecting positive entrance of the yarns into the slots of the respective tubes.

35. In a machine for placing yarns in the tubes of a tube frame the combination with means to lay the yarns, means to trim the yarn ends and mechanism for operating said means, of a power receiving element and connections between the latter and said operating mechanism including a member engageable and disengageable with said ele-

ment to start or stop the machine, means at a plurality of points about the axis of said power-receiving element for controlling the position of said member, and manual means for operating said controlling means to start the machine and to stop the same after predetermined operating periods and with the machine in a plurality of different positions.

10 36. In a machine for placing yarns in the tubes of a tube frame including yarn placing and yarn trimming means and a driving shaft for operating the same, the combination therewith of a power receiving element having a series of lugs arranged about its axis, a member secured to said shaft and movable into and out of the path of said lugs and engageable by one of said lugs thereby to rotate said shaft, spring means urging said member toward said lugs, a manually controllable lever provided with means for permitting engagement of said member and for disengaging the same at a selected one of a plurality of angularly spaced points about the axis of the drive shaft, thereby to stop the machine after an angular movement of the drive shaft corresponding to the angular spacing of said disengaging means.

15 37. In a machine for placing yarns in the tubes of a tube frame including yarn placing and yarn trimming means and a driving shaft for operating the same, the combination therewith of a power receiving element having a series of lugs arranged about its axis, a member secured to said shaft and movable into and out of the path of said lugs and engageable by one of said lugs thereby to rotate said shaft, spring means urging said member toward said lugs, and a manually controllable lever provided with a plurality of members at angularly spaced points about the axis of the driving shaft for permitting engagement of said member

20 to start the machine or for disengaging said

member to stop the machine in a like plurality of different positions of the parts.

37. In a machine for placing yarns in the tubes of a tube frame including yarn placing and yarn trimming means and a driving shaft for operating the same, the combination therewith of a power receiving element having a series of lugs arranged about its axis, a member secured to said shaft and movable into and out of the path of said lugs and engageable by one of said lugs thereby to rotate said shaft, spring means urging said member toward said lugs, a manually controllable lever provided with means for permitting engagement of said member and for disengaging the same at a selected one of a plurality of angularly spaced points about the axis of the drive shaft, thereby to stop the machine after an angular movement of the drive shaft corresponding to the angular spacing of said disengaging means.

In testimony whereof, I have signed my name to this specification.

WALTER BIXBY.
